UNITED STATES PATENT OFFICE.

WILLARD BROAD, OF ASHLAND, MASSACHUSETTS, ASSIGNOR OF ONE-HALF
OF HIS RIGHT TO CHARLES M. ADAMS, OF SAME PLACE.

NUT-LOCK.

SPECIFICATION forming part of Letters Patent No. 224,325, dated February 10, 1880.

Application filed June 30, 1879.

To all whom it may concern:

Be it known that I, WILLARD BROAD, of Ashland, in the county of Middlesex and State of Massachusetts, have invented a new and valuable Improvement in Nut-Locks; and I do hereby declare that the following is a full, clear, and exact description of the construction and operation of the same, reference being had to the annexed drawings, making a part 10 of this specification, and to the letters and figures of reference marked thereon.

Figure 1 of the drawings is a representation of a side elevation of my invention. Fig. 2 is a sectional view taken on line *y y* of Fig. 1. Fig. 3 is a detached view of the locking-plate.

This invention has relation to nut-locks employed for the purpose of connecting together the ends of railroad-rails; and it consists in the peculiar construction of the locking-plate and 20 the manner of connecting it to the rails, as will be hereinafter described, and subsequently pointed out in the claim.

In the accompanying drawings, A B represent two sections of a rail with the usual 25 flange or base *a*. The sections A B are secured together by the ordinary fish-plates *b c* and bolts and nuts *d e*, which pass through said fish-plates and rails.

The locking-plate C is stamped from suitable sheet metal, with the recesses *f* in form 30 to correspond with the form or shape of the nuts *e*. The locking-plate C has a tongue, D, of sufficient length to bend under and against the bottom of the rails transversely to their 35 length, said tongue having a transverse slot, *g*, which passes over and around the contacting edges of the rails, they being cut away at that point, as shown at *h*, upon both sides of the rails to allow the spikes *i* to be driven 40 into the ties E, so that their heads will hug the flanges *a* and prevent any accidental displacement of the locking-plate.

The cutting away of the rails, as shown at *h*, to form a recess when the ends of the rails 45 are in contact, and forming the tongue D, with a transverse slot, *g*, admit of the spikes being driven in closer to the base of the rails, so as to have their heads project farther over the flange, thereby making a firmer fastening and 50 holding the rails more securely to the ties.

The means herein described of locking the nuts removes all danger of their working loose, and the locking-plate being bent under the rails prevents the latter from wearing into the ties or sleepers and dropping one below the other, also giving greater strength to the 55 joints of the rails.

The tongue D is provided at its lower end with the recess *n*, through which a spike, *i*, is driven after the tongue has been bent under 60 the rail, the spike being driven into the cross-tie, and the slot *n* preventing lateral movement of the end of the tongue.

It will be seen that in my construction the locking-plate is secured to the cross-tie and 65 rail-sections by means of the spikes alone, without the employment of auxiliary tongues attached to the locking-plate or other analogous devices, and also that by forming the locking-plate as described, with a central 70 tongue, D, passing under the rail-sections at their junction, and provided with the wings C', having the spaced openings *ff* for the reception of the nuts, much less metal is used in forming the locking-plate than when a sheet- 75 metal shoe is employed lying under the rail-sections with its edges bent up around the rail, and that the bending of said edges is dispensed with.

I am aware that a nut-lock consisting of a 80 plate slotted so as to form three leaves, the two outer leaves adapted to be bent upward around the rail and abutting against the sides of the nuts, and the central leaf fitting upon the sleeper and secured thereto, as shown in Letters 85 Patent granted to I. Allen, dated July 30, 1872, No. 130,003, has heretofore been employed; and I am also aware that a sheet-metal railroad shoe or chair adapted to receive the rail-sections, and having upturned vertical flanges, 90 one of which is provided with spaced slots for the reception of the nuts and perforated attaching-tongues to secure the locking-plate to the cross-ties, the other upturned vertical flange being slotted to receive spikes passing 95 into the cross-ties, as shown in Letters Patent granted to G. H. Coffee, dated June 18, 1878, No. 205,054, has heretofore been employed, and I therefore lay no claim to such inventions.

Having now fully described my invention, 100

what I claim as new, and desire to secure by Letters Patent, is—

The rail-sections A, B, provided with the lower flanges, *aa*, having recesses *h h* at their ends, in combination with the sheet-metal locking-plate C, having the central tongue, D, bent under the rail-sections at their junction, and provided with the slot *g* and recess *n*, and the wings C', made in one piece with the central tongue, and provided with the spaced

openings *ff* for the reception of the nuts, substantially as described, and for the purpose set forth.

In testimony that I claim the above I have hereunto subscribed my name in the presence 15 of two witnesses.

WILLARD BROAD.
